UNITED STATES PATENT OFFICE

LESTER C. GREEN, OF SEATTLE, WASHINGTON

BINDER

Application filed June 17, 1929. Serial No. 371,667.

The invention is a binder of the loose leaf type in which the leaves are permanently held upon concavo-convex rings permanently mounted in the cover.

5 The object of the invention is to provide simple and efficient means for permanently holding rings upon which leaves may be freely mounted, in a binder.

Another object of the invention is to provide 10 a ring for binders which is of such a cross section that leaves will not bind when moved from one position to another thereon.

Another object of the invention is to provide 15 a binder ring which is so shaped that leaves may readily be placed thereon.

A further object of the invention is to provide 20 a ring for binders that may readily be held in the binder with a single connection.

25 And a still further object of the invention is to provide a binder in which the leaves are permanently mounted and at the same time freely held, which is of a simple and economical construction.

With these ends in view the invention embodies 30 a binder having a plurality of concavo-convex rings substantially forming a section of a helix when in the free position and in which the ends of the rings may be placed upon a rivet and permanently held after the leaves have been placed upon them.

Other features and advantages of the invention will be readily understood from the following description taken in connection 35 with the drawings, wherein:

Figure 1 is a view showing the device as it would appear in use.

Figure 2 is a view showing one of the rings mounted in the cover.

40 Figure 3 is a view showing one of the rings in a free position.

Figure 4 is a view showing a cross section through one of the rings, and also showing a portion of one of the leaves mounted thereon.

In the drawing the device is shown as it would be made wherein numeral 1 indicates one of the rings, numeral 2 the binder cover, and numeral 3 the leaves.

45 The rings 1 are made of material having

a concavo-convex cross section, and are formed so that they will substantially form the section of a helix when in the free position, as shown in Figure 3. The ends may have short straight and flat sections as indicated by the numerals 4 and 5 and these sections are provided with openings 6 that may be placed over a tubular rivet 7, as shown in Figure 2. The rivet 7 may be placed through the vertical back of the cover 55 and after the rings have been placed through the openings 8 in the leaves 3 the ends of the rings may be placed over the rivets 7 by placing one end on top of the other and then the head of the rivet may be turned 60 over as shown so that the rings will be permanently held to the vertical back of the binder. The binder back may be reenforced by a plate 9 which may also be placed upon the pin 7 under the ends of the ring, as 65 shown. The rivet may, if desired, be provided with a comparatively large head as indicated by the numeral 10 which will hold the back rigidly against the plate or washer 70 9 when the rivet is drawn tight.

75 It will be understood that although the rings are shown as being of a concavo-convex section they may be made of material of any other shape or design and may be arranged in any other suitable manner.

80 It will be understood that other changes may be made in the construction without departing from the spirit of the invention. One of which changes may be in the use of other means for holding the rings in the 85 cover, another may be in the use of a cover of a different type or design, and still another may be in the formation of the ends of the rings.

85 The construction will be readily understood from the foregoing description. In use the device may be provided as shown and the leaves or pages may be placed upon the rings with the rings in the free position as shown in Figure 3 and then the rivets 90 may be placed through the back of the binder and first one end and then the other end of the rings placed upon the rivets. The end of the rivet may then be turned over 95 or riveted down against the ends of the ring 100

so that the ring will be rigidly held. This will form an inexpensive type of binder of the loose leaf type and in which the leaves are permanently held in the binder and the curvature of the rings will make it possible 5 to move the leaves without having the leaves bind upon the ring.

Having thus fully described the invention what I claim as new and desire to secure by 10 Letters Patent, is:

10. 1. In a binder of the character described, a plurality of concavo-convex open rings conforming to a portion of a helix when in the free position, the ends of the said rings 15 overlapping in the closed position, and means for rigidly and permanently attaching the overlapping ends of the rings to the back of a binder cover.

20. 2. In a binder of the character described, a cover, a plurality of rings, said rings having openings in the ends, and suitable rivets in the back of the binder cover upon which the ends of the rings may be placed, one upon the other, and held.

25. 3. In a binder of the character described, a plurality of open rings upon which the leaves of the binder may be placed, and means for permanently closing, attaching, and rigidly holding the rings to the back 30 of the binder cover.

35. 4. In a binder of the character described, a cover, a plurality of open end rings, and rivets in the back of the binder cover to which the ends of the rings may be permanently attached thereto, and held closed.

In testimony whereof I affix my signature.

LESTER C. GREEN.
